FIRE PROTECTION AUTOMATIC SPRINKLER SYSTEM

Russell W. Gieseler, Jamestown, N. Y.

Application October 31, 1946, Serial No. 706,923

14 Claims. (Cl. 169--5)

1

This invention relates to improvements in fire protection automatic sprinkler systems, and more particularly to an improved wet pipe system having alarm valves and metering devices forming component parts thereof assembled in a manner to effect important economies in installation and operation and improved operating results.

In automatic sprinkler systems heretofore provided, it is common practice to install in the system control devices and instruments intended to give an alarm when a flow of water is escaping from the system, either through the sprinkler heads or because of a leak in the system.

In many localities in the United States, a charge is intended to be made by the water supplier for water consumed due to waste, leakage, or to the opening of a small number of sprinkler heads, whereas no charge is intended to be made for the water consumed when a fire of such gravity occurs as to cause the opening of a substantial number of sprinkler heads.

In the usual sprinkler system employed in such localities, a main check valve is placed in the line leading to the sprinkler system, operable to open and permit unmetered large water flows of water to pass into the system in case of serious fire. In addition, a by-pass metering device is installed intended to measure the wasting water flowing through the system when the main check valve is closed. In addition, an alarm valve is placed at another point on the system in order to give the alarm in case of either waste, leakage or fire. Such installations incorporate a considerable number of valves, control devices and other mechanisms installed as separate and individual operating units.

At present, the owners of many small stores and other businesses which need fire-protection in the form of a sprinkler system, and who would like to take advantage of the reduced fire insurance rates which are in effect when such a system is installed, find themselves financially unable to install a sprinkler system because of the high cost of the various complicated valves, devices and mechanisms necessary to the efficient functioning of the system.

It will be obvious that the smaller the installation, the higher will be the proportionate cost of the various valves and control devices, in comparison with the piping, sprinkler heads and other component parts of the system, since the number of valves and devices required will be the same no matter how many sprinkler heads are attached to the system, and consequently, in modest size systems, the cost, per sprinkler head, to install these various separate valves and devices may well be prohibitive. Further, the flow control devices in systems heretofore used do not accurately and reliably insure the metering of

2

only intended flows in accordance with the terms of the water supply contract.

An object of this invention is to provide an improved fire protection automatic sprinkler system, particularly designed to permit accurate and reliable metering of leakage and waste flows, or flows less than a predetermined amount necessitated by serious fire, which can be economically installed and operated.

Another object of this invention is to provide an improved sprinkler system which can be economically and practically installed and used in small business and residential properties, where automatic sprinkler systems as heretofore designed could not economically be used, thereby enabling small business and residential properties to take advantage of a lower fire insurance rate and at the same time reduce the fire hazard the properties and the community.

A further object of this invention is to provide an improved sprinkler system for fire protection which is delicately sensitive to environment conditions at the point of connection, which embodies into a single economical unit a duplex alarm valve, a main check valve accurately and reliably movable into open flow position only in case of serious fire, and a by-pass valve with meter connection for accurately and reliably measuring leakage and other meterable flows intended to be measured.

Other objects and advantages of this invention will become apparent as the description proceeds.

In accordance with this invention, a fully automatic fire protection sprinkler system is provided wherein water enters the system from a main conduit which is connected to a main valve housing. This valve housing contains a main intake check valve whose operation is delicately controlled by a carefully predetermined weight so that the main check valve moves to open position only in case of a fire involving the opening of more than a predetermined number of sprinkler heads. Thus no water enters the sprinkler system through this accurately weighted check valve until the head in the system above the valve has been reduced to a predetermined point caused by the opening of more than a predetermined number of sprinkler heads. The weight controlling the operation of the main check valve is selected in accordance with the pressure on the water main at the point of installation as compared to the reduced pressure of water out flow into the system through the valve housing when a predetermined number of sprinkler heads are opened.

The main valve housing also contains a by-pass valve which is connected to the discharge end of a short by-pass line whose water entry end is connected to the water main or to the main

valve housing immediately below the main intake check valve. A water measuring meter is situated in the by-pass line to measure the flow therethrough. Slight reduction in the water pressure in the open end of the valve housing caused by line leakage, or flow caused by the opening of a predetermined limited number of sprinkler heads, can be accurately metered and charged against the operator of the property, whereas water flowing through the carefully weighted main check valve, which opens only under predetermined fire conditions, would not be metered, in accordance with the requirements of the water supplier.

Since it is to the interest of the operator of the premises to avoid meter charges as far as possible and accordingly avoid water waste and leakage, this invention contemplates the provision of an alarm system designed to operate when either the main check valve, or the by-pass valve, or both of them, are in open position. The single valve housing containing the weighted main check valve and the by-pass valve, also contains a duplex alarm valve connected by a water line to the operating mechanism of an alarm bell or signal system conveniently located to notify personnel of water flow through the sprinkler system. The duplex alarm valve receives the water from the valve unit housing. The main check valve closure and the by-pass valve closure each have associated therewith a secondary closure element which moves into and out of seating position with the closure seats of the duplex alarm valve simultaneously with the opening and closing movement of the main check valve closure or the by-pass closure respectively.

Thus there is embodied in a single valve unit housing, the main check valve, the by-pass valve and the duplex alarm valve arranged in a manner to provide a compact unit which, is economical to manufacture, and which performs all the functions of the several separately constructed and installed valves and devices heretofore provided. This improved multiple valve unit is also constructed so as to permit the repair of water meters and the like without impairing the function of the sprinkler system as a whole in case of fire.

It will be further appreciated that the water pressure in the community mains will vary depending upon the elevation of the property where the sprinkler system is installed, and the elevation of the installed alarm meter. Systems now in use do not take into account pressure variations at different property sites, so that a main check valve installed on a low pressure main would not open until a relatively large flow of water is passing through the sprinkler heads of the system. Thus a relatively large volume of water may flow through the metering by-pass line, which should not have been metered, but should have flowed through an open main check valve.

Conversely, if the property is located on a high pressure main, the main check valve would open for a relatively small flow of water passing through the sprinkler system, which small flow should have passed through the metering by-pass line. This invention makes provision for a variable weighting device which controls the operation of the main intake check valve, which device has an accurately gauged and determined weight, which will delicately resist opening of the main check valve until the point is reached where an

exact and intended amount of water flow will properly open the main check valve. The weighting device, which is weighted to the conformed circumstances of the installation, may be protected against tampering by the water supplier with a tamper proof cover.

Although the characteristic features of this invention will be particularly pointed out in the claims appended hereto, the invention itself, and the manner in which it may be carried out, may be better understood by referring to the following description taken in connection with the accompanying drawings forming a part hereof, in which

15 Fig. 1 is a side elevational view of the improved alarm sprinkler system, the building in which it is installed being diagrammatically illustrated;

Fig. 2 is an enlarged side view of a main operating mechanism of the system;

20 Fig. 3 is an enlarged side elevational view of the improved multiple purpose valve assembly, with meter by-pass attachment;

Fig. 4 is a horizontal cross-section of the multiple purpose valve assembly, this section being taken on line 4-4 of Fig. 3;

25 Fig. 5 is a vertical cross-section of the valve assembly showing the main check valve and the by-pass check valve in closed position, the closed position thereof being illustrated by dotted lines, this section being taken on line 5-5 of Fig. 4;

Fig. 6 is a side view of the weight arm associated with the main check valve clapper illustrated in Fig. 4, as the same appears when viewed along line 6-6 of Fig. 4;

30 Fig. 7 is a horizontal cross-section of the multiple purpose valve assembly in which a weight block of carefully determined weight is mounted on and supported by the main check valve clapper;

40 Fig. 8 is a vertical cross-sectional view of the valve assembly as the same appears when viewed along line 8-8 of Fig. 7, this view showing the check valves in open position;

Fig. 9 is a fragmentary cross-sectional view 45 taken through the main check valve and associated clapper as the same appears when viewed along line 10-10 of Fig. 7; and

Fig. 10 is a fragmentary cross-sectional view of the main check valve showing the manner in 50 which the weight block is attached thereto as the same appears when viewed along line 11-11 of Fig. 7.

Similar reference characters refer to similar parts throughout the several views of the drawings and specification.

There is illustrated in Fig. 1 this improved sprinkler system as it may be installed in a typical six story building, having an outside wall 21, a roof 22 and a series of floors 23. The improved sprinkler system as shown in Figs. 1 and 2 generally comprises an intake conduit 3 leading from a water main 4, and which makes connection with the valve housing 6. The conduit 3 is fitted with a gate valve 2 by means of which water

65 may be prevented from flowing into the system when it is shut down for repairs. A by-pass conduit 8 leads from the base of the valve housing 6 to a water meter 10. The by-pass conduit 8 is provided with a gate valve 9 so that the meter 10 may be removed for inspection or repair without interrupting the flow of water into the main valve housing 6 through the main intake 27 in case of fire when the meter is removed.

Water flowing through the water meter 10 is 70 returned to the system at the valve housing 6

through a conduit 11. From the valve housing 6 another conduit 12 leads to an alarm mechanism which may be either a water meter or a hydrostatic switch, or both. For purposes of illustration, there is shown in Fig. 2 a combination of a water motor 13 attached to an outside gong 14, and a hydrostatic switch 15, which actuates an electrical alarm 16 when tripped by water pressure in the conduit 12. The conduit 12 may include a retarding chamber 17, so that false alarms will not be given in case of water hammer. From the valve housing 6 an outlet conduit 18 connects with distributor pipes 19, to which are attached sprinkler heads 20 at the various floors.

The improved multiple purpose valve assembly consists of a valve housing 6 fitted with flanges 24 and 24' by means of which a connection can be made with the main conduit 3 and the outlet conduit 18 respectively. The valve housing 6 is fitted with a removable plate 25 by means of a plurality of bolts 26, thus affording easy access to the interior of the housing for repairs and adjustments. The valve housing 6 is provided with a main intake port 27, a main outlet port 28, a bypass outlet port 29 through which water may flow to the water meter 10, a bypass intake port 30 through which water passing through the meter 10 may reenter the main valve housing 6, and a bleeder outlet port 31, through which water may flow from the valve housing 6 to actuate the alarm mechanism 13 and 14 and the alarm mechanism 16.

The valve housing 6 is also provided with port 43, through which the water in the system may be drained through a conduit 12, when it is desired to make repairs in the system. The conduit 12 is fitted with a gate valve 73, which is opened when it is desired to drain the system. Gate valve 2 must be closed when draining, to prevent flow of water from the main 1 into the system. For inspection purposes, two other ports 44 and 44' are provided, located above and below the main intake check valve, through which water may flow through conduits 45 and 45' to pressure gauges 46 and 46' respectively.

At the point where the main intake port 27 enters the main chamber 36 of the main valve housing, there is provided a valve seat 37, which is preferably of bronze or some similar tough but easily machined metal. Similarly, at the point where the bypass inlet port 30 from the water meter 10 enters the main chamber 36 of the valve assembly, there is provided a similar but smaller valve seat 38.

The bleeder outlet port 31 is provided with a hollow semi-spherical cap 32, in which are bored two port holes 33 and 34, which are provided with valve seats. The cap 32 is provided with a threaded neck 35 so that a watertight connection may be made with the valve housing 6. This, of course, is merely a preferred exemplification of this detail, since the cap 32 may be welded to the valve housing 6 over the port 31.

The valve housing 6 contains a fulcrum block 39 upon which the main intake check clapper arm 40 may swing, and a fulcrum block 41 upon which the bypass intake check clapper arm 42 may swing.

The main check valve comprises the clapper arm 40 which is fixed to a stud shaft 47, as by set screw 53. The ends of the stud shaft extend into bearing openings in the paired fulcrum blocks 39, whereby the clapper arm 40 is free to pivot with a minimum of friction. A closure disc 48 is suitably fixed to the clapper arm

40 and is designed to fit snugly into the valve seat 37 when the main intake check valve is closed.

In the form of the invention shown in Figs. 4 and 5, the closure disc 48 is rigidly fixed to the clapper arm 40 as by nut and bolt 52. In the form of the invention shown in Figs. 7, 8 and 9, the closure disc 48 is pivotally connected to the clapper arm 40 whereby the closure disc will 10 adjust itself into a snug seating position with respect to the valve seat 37. This is effected by providing the closure disc 48 with a pair of spaced upstanding lugs 49 and a hinge pin 50 which extends through aligned apertures in the lugs 49 and the clapper arm 40.

In the form of the invention shown in Figs. 4 and 5, the clapper arm 40 is weighted by a weighting device which comprises a small diameter rod 54 fixed to and extending from the stud shaft 47, shown more particularly in Figs. 4 and 6. The rod 54 extends through a hole in the wall of the valve housing, a water-tight bearing 56 being provided designed to assure the water-tight and leak proof seal. A weight or scale arm 66 is secured to and extends laterally from the projecting end of the rod 54. A weight bucket 68 is suspended from the weight arm 66. The bucket is weighted with sand or metal shot 69 so that the weight may be delicately and accurately controlled. The weight arm 66 should be sufficiently long to insure adequate leverage action and preferably should be approximately the same length as the clapper arm 40.

When the main check valve is in the fully open position as illustrated in Fig. 5, the main check clapper arm 40 rests against a stop 57. It will also be observed that when the main intake check valve is in the fully open position, the weight arm 66 will also rise in cooperation with it, and the center of gravity of the weight 69 will shift to such an extent that little or no frictional resistance is offered to the passage of water through the valve housing 6, but will nevertheless provide sufficient leverage action to 45 drop the main intake check valve into closed position automatically when the flow ceases.

The weight arm 66, weight receptacle 68, and weight 69 are protected by a cover shell 70 which is attached to the valve housing 6 by means of 50 hinges 71, and which may be protected against tampering by means of a padlock 80 passed through a staple 81 or by means of a tamper-proof seal. The dimensions of the cover shell 70 should be such as to allow free movement of the weight arm 66 when it rises in cooperation with the rising of the main intake clapper arm 40.

In the form of the invention shown in Figs. 7 to 10 inclusive, a weight block 75, whose weight is accurately determined, is attached to the main clapper arm 40 and is supported thereby. As shown more particularly in Fig. 10, the lower face of the weight block 75 may be provided with a recess cavity 76 shaped to snugly receive the clapper arm 40. A securing pin 77, extending 65 through an aligned aperture in the weight block 75 and the clapper arm 40, may be used to secure the weight block 75 to the clapper arm. The securing pin 77 may be provided with a tamper proof seal 78 so that the holding nut 79 cannot 70 be removed from the pin 77, or the pin 77 removed from the weight block 75, without leaving evidence of tampering. The weight block 75 is carefully weighted so as to hold the closure disc 48 in its valve seating position until the intended differential on the opposite sides of the valve

closure disc is reached, whereupon the clapper arm 40 and the associated closure disc swings into valve opening position.

The by-pass intake check valve comprises a clapper arm 42 hingedly connected to the fulcrum blocks 41 by means of a pivot bolt 58, upon which the clapper arm 42 is free to swing. A closure disc 59 is attached to the clapper arm 42 as by means of a bolt 60. The closure disc 59 is designed to fit snugly against the valve seat 38 when the by-pass intake check valve is in closed position.

The valve housing 6 is provided with a stop 64 against which the clapper 42 rests when in fully open position. The clapper 42 carries an arm extension 61 to which is secured a closure disc 62 by means of a nut and bolt 63. The closure disc 62 is designed to fit securely onto the seat in the port 34 of the alarm cap 32 when the by-pass intake check valve is in the closed position, forming a water-tight connection therewith.

When the system is placed in operation, all pipes are filled with water with the exception of the alarm water line 12. When a leak occurs in the system, or if a permitted limited number of sprinkler heads 20 are opened, the resulting reduced pressure in the valve chamber 36 will cause the by-pass intake clapper 42 to rise, and water will flow through the by-pass outlet port 29 and by-pass conduit 8 to the meter 10, where the consumption of water is recorded, and thence through the by-pass conduit 11 and through the inlet by-pass port 38 into valve chamber 36. When the by-pass intake clapper 42 rises, it will be seen that the closure disc 62 covering the alarm bleeder port 34 is also raised, allowing water to flow into the conduit 12 and thence to alarm devices 13 and 15, and thus cause an alarm to be sounded.

A substantial decrease in the pressure head in the valve chamber 36, due to the opening of a number of sprinkler heads of fire hazard proportions and large enough to cause a flow of water through the system larger than the intended maximum gallonage per minute to be passed through the meter, will cause the pressure of water in the main intake 27 to lift the main intake check valve closure 48, thus insuring a large supply of water to the fire. The water entering the system through the main intake 27 would usually not be metered.

When it is desired to remove the meter 10 for inspection or repair, the gate valve 9 is closed, thus shutting off any flow of water through conduit 8 to the meter 10. When the gate valve 9 is closed, the by-pass check valve will also be in closed position, and thus prevent any back flow of water from the main chamber 36 into the conduit 11. Hence, in this system, the meter 10 can be removed without any loss of water from the system and the system will remain fully operative in case of fire. It will also be observed that should the by-pass line 8 and 11 be cut off for repairs, any decrease in head in the valve chamber 36 will cause the pressure in the main intake 27 to force open the main intake check valve and simultaneously disengage the closure disc 51 from the port 33, allowing water to flow into the conduit 12, and thence to alarm devices 13 and 15, thus insuring an effective alarm under all conditions of operation in the system.

Statistics gathered by fire underwriters indicate that when fires occur in a building protected by an automatic fire protection sprinkler system, the majority are small fires which do not involve the opening of more than three sprinkler heads.

For this reason, water suppliers who insist that the owner of the automatic fire-protection sprinkler system pay for wastage, leakage, and water consumption due to the opening of a small number of sprinkler heads, usually provide in their contracts that the customer shall pay for all flows up to the amount of flow which would occur when three sprinkler heads are open, the supplier assuming the cost when greater flows occur.

Automatic sprinkler systems as heretofore designed and installed generally fail to function in a manner to accurately effectuate and make possible the true intent of such a contract.

This invention provides a multiple purpose valve unit which is delicately sensitive and which is adjusted to accurately divert water up to a predetermined gallonage per minute through the meter, and will direct flows in excess of such amount to pass through the system unmetered in accordance with the true intent of the water supply contract.

This desirable result is accomplished by weighting the main valve clapper arm 40 carefully and accurately to effect diversion of an exactly predetermined and permitted maximum gallonage per minute through the by-pass conduits 8 and 11 and the meter 10 before the valve closure disc 48 is raised. By thus weighting the main check closure disc 48, flow through the main check valve is prevented, and all the flow diverted through the by-pass conduits 8 and 11, until sufficient differential in water pressure has been built up between that in the main intake port 27 and in the main valve chamber 36 to raise the weighted clapper arm 40. It will be appreciated that a flow of water passing through the by-pass circuit will make a difference in pressure between that in the main intake port 27 and that in the main valve housing 36 proportional to the frictional resistance offered by the by-pass 8 and 11 and the meter 10. It is obvious that the greater the weight applied to the clapper arm 40, the greater will be the maximum amount of gallonage per minute passing through the by-pass conduits 8 and 11 and the meter 10 before the main clapper arm 40 moves to open position.

In the form of the invention shown in Figs. 4, 5 and 6, the amount of weight 69 which should be placed in the weight receptacle 68 may be accurately and easily determined as follows: With gate valve 9 open, so that water may flow through the by-pass conduits 8 and 11 and the meter 10, the required number of sprinkler heads 20, for instance three, are opened, and weights 69 are placed in the weight bucket 68 until sufficient weight has been added to maintain the main clapper arm 40 in a closed position. One additional sprinkler head 20 is then opened, and observation is made to determine whether or not the main clapper arm 40 rises. If it does not, weight 69 is removed from the weight bucket 68 until it opens.

In the form of the invention shown in Figs. 7 to 10 inclusive, a weight block 75 of the correct weight would be attached to the clapper arm 76 by the inspector. These weight blocks may be formed of a solder material which can be added to or subtracted from the main body of weight block so as to vary its weight. By reading pressure gauges 46 and 46', the pressure conditions in the valve housing 6 when three and four sprinkler heads are opened may be readily determined. With such pressure differential readings at hand, an inspector may make use of

tables prepared by the manufacturer of these valves, which tables would indicate the proper weight to apply to the clapper arm 40 to maintain the valve closure member 48 in closed position when three sprinkler heads are open, and to permit opening of the closure member 48 when four sprinkler heads are open. With a little experience, an inspector can quickly determine and sense the correct weight block 75 to apply to the clapper arm 40. For convenience, the inspector may carry an assortment of weight blocks of indicated varying weight, and suitable to satisfy almost any pressure condition which he may encounter.

After the system has been in use for some time, it will be appreciated that due to rusting or other defects in the system, the flow characteristics of the system may change slightly. In such an event, the tests given above may be repeated, and the amount of weight 69 or 75 may easily and accurately be changed to reflect changed conditions in the system.

This improved sprinkler system is simple and sturdy in construction, with a minimum of movable parts requiring attention, and is easy to keep in repair. It is low in cost, and well adapted for installation in buildings which up to now have not been protected from fire due to the high cost of installation of systems now in use.

While certain novel features of the invention have been disclosed herein, and are pointed out in the annexed claims, it will be understood that various omissions, substitutions and changes may be made by those skilled in the art without departing from the spirit of the invention.

What is claimed is:

1. In a fire protection sprinkler system having a water distribution and sprinkler head system supplied by a primary outlet conduit which in turn is supplied by a main intake conduit, including in combination, a main valve housing connecting said outlet conduit and main intake conduit, a main check valve having a closure member contained within said valve housing for controlling the flow from said intake conduit to said outlet conduit, a by-pass conduit connected to receive water from said main intake conduit below said main check valve and connected to discharge the water into the system at the outflow side of said main check valve, said by-pass conduit including as a part thereof a secondary check valve independent of said main check valve, and a weight device operably connected to the closure member of said main check valve whereby the opening movement of said closure member may be controlled in accordance with a predetermined pressure differential existing between the intake and outlet sides of said closure member.

2. In a fire protection sprinkler system having a water distribution and sprinkler head system supplied by a primary outlet conduit which in turn is supplied by a main intake conduit, including in combination, a main valve housing connecting said outlet conduit and main intake conduit, a main check valve having a closure member contained within said valve housing for controlling the flow from said intake conduit to said outlet conduit, a by-pass conduit connected to receive water from said main intake conduit below said main check valve and connected to discharge the water into the system at the outflow side of said main check valve, said by-pass conduit including as a part thereof a secondary check valve independent of said main check

valve, and a weight device operably connected to the closure member of said main check valve whereby the opening movement of said closure member may be variably controlled in accordance with a predetermined pressure differential existing between the intake and outlet sides of said closure member, said variable weight device including a weighted scale arm exterior to said main valve housing, and means extending through the adjacent wall of said housing for connecting said scale arm to said closure member and operable to retain said closure member in closed position until said predetermined pressure differential is exceeded.

3. In a fire protection sprinkler system having a water distribution and sprinkler head system supplied by a primary outlet conduit which in turn is supplied by a main intake conduit, including in combination, a main valve housing connecting said outlet conduit and main intake conduit, a main check valve having a closure member contained within said valve housing for controlling the flow from said intake conduit to said outlet conduit, a by-pass conduit connected to receive water from said main intake conduit below said main check valve and connected to discharge the water into the system at the outflow side of said main check valve, said by-pass conduit including as a part thereof a secondary check valve independent of said main check valve, and a weight device including a weighted scale arm operably connected to the closure member of said main check valve whereby the opening movement of said closure member may be controlled in accordance with a predetermined pressure differential existing between the intake and outlet sides of said closure member, and means extending through a wall of said housing for connecting said scale arm to said closure member, said weighted scale arm being operable to retain said closure member in closed position until said predetermined pressure differential is exceeded.

4. In a fire protection sprinkler system having a water distribution and sprinkler head system supplied by primary outlet conduit which in turn is supplied by a main intake conduit, including in combination, a main valve housing connecting said outlet conduit and main intake conduit, a main check valve having a closure member contained within said valve housing for controlling the flow from said intake conduit to said outlet conduit, a by-pass conduit connected to receive water from said main intake conduit below said main check valve and connected to discharge the water into the system at the outflow side of said main check valve, said by-pass conduit including as a part thereof a secondary check valve independent of said main check valve and a water meter designed to measure and record the volume flow through said by-pass conduit, and a weight device operably connected to the closure member of said main check valve whereby the opening movement of said closure member may be controlled in accordance with a predetermined pressure differential existing between the intake and outlet sides of said closure member as determined by the intended metered flow through said by-pass conduit and the intended unmetered flow through said main check valve.

5. In a fire protection sprinkler system having a water distribution and sprinkler head system supplied by a primary outlet conduit which in turn is supplied by a main intake conduit, including in combination, a main valve housing con-

necting said outlet conduit and main intake conduit, a main check valve having a closure member contained within said valve housing for controlling the flow from said intake conduit to said outlet conduit, a by-pass conduit connected to receive water from said main intake conduit below said main check valve and connected to discharge the water into the system at the outflow side of said main check valve, said by-pass conduit including as a part thereof a secondary check valve independent of said main check valve and a water meter designed to measure and record the volume flow through said by-pass conduit, and a weight device operably connected to the closure member of said main check valve whereby the opening movement of said closure member may be controlled in accordance with a predetermined pressure differential existing between the intake and outlet sides of said closure member as determined by the intended metered flow through said by-pass conduit and the intended unmetered flow through said main check valve, said weight device including a weighted scale arm exterior to said main valve housing, and means extending through a wall of said housing for connecting said scale arm to said closure member and operable to retain said closure member in closed position until said predetermined pressure differential is exceeded.

6. In a fire protection sprinkler system having a water distribution and sprinkler head system supplied by a primary outlet conduit which in turn is supplied by a main intake conduit, including in combination, a main valve housing connecting said outlet conduit and main intake conduit, a main check valve having a hinged closure member contained within said valve housing for controlling the flow from said intake conduit to said outlet conduit, a secondary check valve within said valve housing having a closure member therefor, a by-pass conduit leading from said main intake conduit to said secondary check valve, a weight device operably connected to the closure member of said main check valve whereby the opening movement of said closure member may be controlled in accordance with a predetermined pressure differential existing on the intake and outlet side of said closure member, said weight device including a weighted scale arm, a rotatable shaft extending through a wall of said housing for connecting said scale arm to said hinged closure member and operable to retain said closure member in closed position until said predetermined pressure differential is exceeded, and a cover closure for said weighted scale arm having means for sealing same in closed position.

7. In a fire protection sprinkler system having a water distribution and sprinkler system supplied by a primary outlet conduit which in turn is supplied by a main intake conduit, and an alarm device operably connected to a water line, said system including in combination, a plural purpose valve housing connecting said outlet conduit and main intake conduit, a main check valve having a closure member contained within said valve housing for controlling the flow from said intake conduit to said outlet conduit, a secondary check valve within said valve housing having a closure member therefor, a by-pass conduit leading from said main intake conduit to said secondary check valve within said valve housing, a bleeder port in said valve housing having a flow connection to the water line of said alarm device, and a closure element associated with the closure member of said main check valve operative to

close and open said bleeder port with the closing and opening movement of the closure member for said main check valve.

8. In a fire protection sprinkler system having a water distribution and sprinkler system supplied by a primary outlet conduit which in turn is supplied by a main intake conduit, and an alarm device operably connected to a water line, said system including in combination, a plural purpose valve housing connecting said outlet conduit and main intake conduit, a main check valve having a closure member contained within said valve housing for controlling the flow from said intake conduit to said outlet conduit, a secondary check valve within said valve housing having a closure member therefor, a by-pass conduit leading from said main intake conduit to said secondary check valve within said valve housing, a bleeder port in said valve housing having a flow connection to the water line of said alarm device, and a closure element associated with the closure member of said secondary check valve operative to close and open said bleeder port with the closing and opening movement of the closure member for said secondary check valve.

9. In a fire protection sprinkler system having a water distribution and sprinkler system supplied by a primary outlet conduit which in turn is supplied by a main intake conduit, and an alarm device operably connected to a water line, including in combination, a plural purpose valve housing connecting said outlet conduit and main intake conduit, a main check valve having a closure member contained within said valve housing for controlling the flow from said intake conduit to said outlet conduit, a secondary check valve within said valve housing having a closure member therefor, a by-pass conduit leading from said main intake conduit to said secondary check valve within said valve housing, a bleeder outlet in said valve housing having a flow connection to the water line of said alarm device, said bleeder outlet having a pair of outlet ports, a closure element associated with the closure member of said main check valve operative to close one of said bleeder ports with the closing and opening movement of the closure member for said main check valve, and a closure element associated with said secondary check valve operative to close said second bleeder port with the closing and opening movement of the closure member for said secondary check valve.

10. In a fire protection sprinkler system having a water distribution and sprinkler system supplied by a primary outlet conduit which in turn is supplied by a main intake conduit, and an alarm device operably connected to a water line, including in combination, a plural purpose valve housing connecting said outlet conduit and main intake conduit, a main check valve having a closure member contained within said valve housing for controlling the flow from said intake conduit to said outlet conduit, a secondary check valve within said valve housing having a closure member therefor, a by-pass conduit leading from said main intake conduit to said secondary check valve within said valve housing, said by-pass conduit having a water meter for measuring the flow therethrough, a bleeder outlet in said valve housing having a flow connection to the water line of said alarm device, said bleeder outlet having a pair of outlet ports, a closure element associated with the closure member of said main check valve operative to close one of said bleeder ports with the closing and opening movement of

the closure member for said main check valve, and a closure element associated with said secondary check valve operative to close said second bleeder port with the closing and opening movement of the closure member for said secondary check valve.

11. In a fire protection sprinkler system having a water distribution and sprinkler system supplied by a primary outlet conduit which in turn is supplied by a main intake conduit, said system including in combination, a plural purpose valve housing connecting said outlet conduit and main intake conduit, a main check valve having a closure member contained within said valve housing for controlling the flow from said intake conduit to said outlet conduit, a secondary check valve within said valve housing having a closure member therefor, a by-pass conduit leading from said main intake conduit to said secondary check valve within said valve housing, said by-pass conduit having a water meter for measuring the flow therethrough, and a weight device operably connected to the closure member of said main check valve whereby the opening movement of said closure member may be controlled in accordance with a predetermined pressure differential existing between the intake and outlet sides of said closure member.

12. In a fire protection sprinkler system having a water distribution and sprinkler system supplied by a primary outlet conduit which in turn is supplied by a main intake conduit, and an alarm device operably connected to a water line, said system including in combination, a plural purpose valve housing connecting said outlet conduit and main intake conduit, a main check valve having a closure member contained within said valve housing for controlling the flow from said intake conduit to said outlet conduit, a secondary check valve within said valve housing having a closure member therefor, a by-pass conduit leading from said main intake conduit to said secondary check valve within said valve housing, a bleeder port in said valve housing having a flow connection to the water line of said alarm device, a closure element associated with the closure member of said main check valve operative to close and open said bleeder port with the closing and opening movement of this closure member for said main check valve, and a weight device operably connected to the closure member of said main check valve whereby the opening movement of said closure member may be controlled in accordance with a predetermined pressure differential existing between the intake and outlet sides of said closure member.

13. In a fire protection sprinkler system having a water distribution and sprinkler system supplied by a primary outlet conduit which in turn is supplied by a main intake conduit, and an alarm device operably connected to a water line, said system including in combination, a plural purpose valve housing connecting said outlet conduit and main intake conduit, a main check valve having a closure member contained within said valve housing for controlling the flow from said intake conduit to said outlet conduit, a secondary check valve within said valve housing having a closure member therefor, a by-pass conduit leading from said main intake conduit to said secondary check valve within said valve housing, said by-pass conduit having a water

meter for measuring the flow therethrough, a pair of bleeder ports in said valve housing having a flow connection to the water line of said alarm device, a closure element associated with the closure member of said main check valve operative to close one of said bleeder ports with the closing and opening movement of the closure member for said main check valve, a closure element associated with said secondary check valve to close said second bleeder port with the closing and opening movement of the closure member for said secondary check valve, and a weight device operably connected to the closure member of said main check valve whereby the opening movement of said closure member may be controlled in accordance with a predetermined pressure differential existing between the intake and outlet sides of said closure member.

14. In a fire protection sprinkler system having a water distribution and sprinkler system supplied by a primary outlet conduit which in turn is supplied by a main intake conduit, and an alarm device operably connected to a water line, said system including in combination, a plural purpose valve housing connecting said outlet conduit and main intake conduit, a main check valve having a closure member contained within said valve housing for controlling the flow from said intake conduit to said outlet conduit, a secondary check valve within said valve housing having a closure member therefor, a by-pass conduit leading from said main intake conduit to said secondary check valve within said valve housing, said by-pass conduit having a water meter for measuring the flow therethrough and a shut-off valve located on the by-pass conduit between the main intake conduit and the meter, a pair of bleeder ports in said valve housing having a flow connection to the water line of said alarm device, a closure element associated with the closure member of said main check valve operative to close and open one of said bleeder ports with the closing and opening movement of the closure member for said main check valve, a closure element associated with the closure member of said secondary check valve operative to close and open the second bleeder port with the closing and opening movement of the closure member for said secondary check valve, and a weight device operably connected to the closure member of said main check valve whereby the opening movement of said closure member may be controlled in accordance with a predetermined pressure differential existing between the intake and outlet sides of said closure member, said weight device including a weighted scale arm, and means extending through a wall of said housing for connecting said scale arm to said closure member, said weighted scale arm being operable to retain said closure member in closed position until said predetermined pressure differential is exceeded.

RUSSELL W. GIESELER.
